UNITED STATES PATENT OFFICE.

ROBERT H. LIEBERTHAL, OF BRIDGEPORT, CONNECTICUT, ASSIGNOR TO THE ALL-IN-ONE MANUFACTURING COMPANY, INCORPORATED, OF BRIDGEPORT, CONNECTICUT, A CORPORATION OF CONNECTICUT.

COMBINATION TOOTHBRUSH AND HOLDER.

Application filed November 29, 1922. Serial No. 604,023.

To all whom it may concern:

Be it known that I, ROBERT H. LIEBERTHAL, a citizen of the United States, residing at Bridgeport, county of Fairfield, State of Connecticut, have invented an Improvement 5 in Combination Toothbrushes and Holders, of which the following is a specification.

This invention relates to tooth brushes, and has for an object to provide an improved brush of the type having that portion 10 of the brush which serves as a handle adapted to carry a dentifrice.

It is also an object of the invention to provide a device of this character which will be 15 simple in construction and may be easily kept clean and sanitary at all times.

It is a further object of the invention to provide a structure in which the supply of dentifrice may be easily and quickly renewed, and also in which the bristle head 20 of the brush may be easily and quickly positioned adjacent the discharge nozzle of the dentifrice tube to receive dentifrice therefrom, and may also be positioned at a 25 distance therefrom for use in cleaning the teeth.

It is a still further object of the invention to provide a device of this character in which the brush proper comprising the 30 bristle head may be easily renewed, and it is a still further object of the invention to provide a device of this character which will carry a supply of dental floss and will carry it in such a manner that it will be 35 easily accessible when desired for use.

With the foregoing and other objects in view, I have devised the construction illustrated in the accompanying drawing, in which—

40 Fig. 1 is a side elevation of the complete article enclosed in its casing.

Fig. 2 is an end view thereof looking from the right of Fig. 1.

Fig. 3 is a side elevation of the brush and 45 handle removed from the casing showing the bristle head in position for use.

Fig. 4 is a top plan view of one end of the casing, substantially on line 4—4 of Fig. 1.

50 Fig. 5 is a detailed sectional view at the other end of the device substantially on line 5—5 of Fig. 1.

Fig. 6 is a longitudinal sectional view of

the device removed from the casing, showing the bristle head in position to receive dentifrice from the dentifrice tube.

55

Fig. 7 is a transverse section substantially on line 7—7 of Fig. 6.

Fig. 8 is a transverse section substantially on line 8—8 of Fig. 6.

Fig. 9 is a transverse section substantially 60 on line 9—9 of Fig. 6.

Fig. 10 is an end view of the handle showing the cover for the dental floss container.

Fig. 11 is an end view of the dentifrice 65 container, and

Fig. 12 is a detailed sectional view of a portion of the discharge nozzle showing the controlling valve.

The enclosing casing indicated at 13 is 70 preferably a sheet metal shell closed at one end 14 and open at the other end for insertion of the brush and dentifrice container, and shaped in cross sections substantially as shown in Fig. 2. At its closed end it is provided on its opposite sides with ventilating 75 openings 15 and on the top with similar ventilating openings 16, as this is the end in which the bristle head is located when the brush is enclosed in the casing, and these openings allow circulation of air to maintain 80 ventilation and allow the brush to dry.

The dentifrice tube holding member and 85 handle for the brush is indicated at 17 and is provided on its upper side with a longitudinally extending pocket or recess 18 in which is adapted to be seated a dentifrice container 19 which is the usual collapsible tube, but is preferably provided with an improved discharge nozzle and controlling 90 means therefor disclosed in my co-pending application, Serial No. 593,612, filed October 10, 1922. At the opposite ends of the recess 18 are upwardly extending end walls 20 and 21, the wall 21 being provided with an opening through which the discharge nozzle 22 95 of the container 19 may be extended, this nozzle being preferably provided with a portion 23 adapted to fit this opening. Within the recess 18 and pivoted to the wall 20 is a retaining member 24 preferably a flat spring pivoted to the end wall at 25 and adapted to engage the flattened sealed end of the dentifrice tube 19, and thus the tube will be 100 securely held in the recess. By swinging

Fig. 6 is a longitudinal sectional view of

member 24 to one side on its pivot the empty tube may be easily removed and a new filled tube substituted therefor.

On the opposite side of the handle 17 is mounted the tooth brush proper comprising a bristle head 27 and a shank 28. The handle is preferably provided with a longitudinally extending recess 29 having side walls 30 between which the shank of the brush is pivoted by means of transversely extending pin 31. The end of the brush shank is slit, as shown at 32, and provided with a transverse opening 33 in this slit to receive the pin 31. The material of which the shank is made is sufficiently resilient to allow the portion thereof on opposite sides of the slit to yield to allow the pin 31 to pass from the end of the shank to the opening 33, and yieldingly retain the same therein, so that by merely forcing the pin into the slot the brush will be mounted in the handle, or by pulling on the same it may be removed for easy renewals. Extending longitudinally of the recess 29 beneath the shank is a flat spring 34 bearing against the shank, which will thus retain the brush with its bristle head either adjacent the discharge nozzle 22 as shown in Fig. 6, or hold it extended in the opposite direction for use as shown in Fig. 3.

The bristle head comprises a plurality of rows of bristle with the longitudinal central rows 35 shorter than the side rows 36 so as to provide a sort of longitudinally extending trough at the top of the bristles in which the discharge nozzle 22 is preferably positioned when the bristle head is in the position shown in Figs. 6 and 9 to receive a supply of dentifrice. The nozzle 22 is provided with a lateral discharge opening 37 and this nozzle is preferably of such a length that this discharge opening is substantially midway the length of the bristle head, although it may be given other locations if desired. This opening is controlled by a plunger or piston 38 fitting the interior of the tube or nozzle and slideable longitudinally therein to and from a position over this discharge opening to close the same, as shown in Fig. 12, or to a position to uncover the same, as shown in Fig. 6. The piston is provided with a shank 39 projecting from the end of the nozzle provided with a suitable flat head 40 and with laterally projecting lugs 41. The opening in the end of the nozzle for passage of the shank has two lateral slots for the passage of these lugs so that when the piston is moved inwardly to cover the discharge opening, rotation of the plunger will bring the lugs 41 into alignment with the end walls of the discharge nozzle and secure this plunger in closed position. When it is desired to discharge dentifrice from the tube by turning the plunger back to bring these lugs into alignment with the

slots in the end of the nozzle, pressure applied to the body of the tube 19 will force the plunger outwardly and will uncover the discharge opening. A suitable mark, as an arrow, may be placed on the discharge nozzle 70 to indicate when the plunger is in unlocked position.

Within the body of the handle 17 and between the two recesses 18 and 29 for the dentifrice container and the brush, is a pocket 42 to carry a supply of dental floss 43. This is preferably a long coil inserted in a separate sanitary container comprising a glass tube 44 which may be inserted through the open end of this pocket, the opening through this pocket being in the end wall of the handle. Pivoted to this end wall as by a suitable rivet 45 is a cover plate 46 of a shape substantially the shape of the end of the handle and provided with a recess 47 in one side thereof adapted to receive a pin or lug 48 carried by the handle to yieldingly retain this cover plate in closed position, and suitable stop means such as a pin 49 adapted to enter a notch 50 may be provided to limit movement of this plate in one direction. The plate is also provided with a notch for passage of the floss, as shown in Fig. 2, and the cover plate also is provided with a cutter 52, preferably struck up therefrom, for cutting the floss to lengths as desired. When the cover plate 46 is in closed position the free end of the floss is clamped between this plate and the end of the handle, so that this free end is held in 100 position where it is easily accessible.

The outer end of the handle adjacent the plate 45 is provided on the opposite sides thereof with recesses 53 providing shoulders 54 for insertion of the thumb and finger to facilitate the removal of the handle and brush from the casing 13. The casing is provided adjacent its open end on the opposite sides thereof with notches 55, so located that when the brush and handle are inserted in the casing they will be in alignment with the recesses 53 and allow gripping of the same with the thumb and finger. The walls of the casing 13 are bent inwardly somewhat at the inner end of the notches 55 as 115 shown at 56 to yieldingly engage in these notches and prevent accidental removal of the handle from the casing.

It will be apparent from the foregoing description that as the casing 13 is smooth and unobstructed on its outer surface the complete article will form a neat and simple package which may be easily carried, and that the ventilating openings 15 and 16 provide the required ventilation and keep the brush dry when not in use. When it is desired to use the brush, by merely gripping the recesses and shoulders 24 with the thumb and finger, the handle, brush and dentifrice container may be withdrawn from the cas- 130

ing. The piston or plunger 38 may then be unlocked by turning the head 40 to bring the lugs 41 into alignment with the grooves in the end of the nozzle. Then by merely 5 pressing of the fingers on the side of the container 19 pressing this container against the bottom of the recess 18, dentifrice will be forced into the nozzle moving the plunger 38 away from the discharge opening 37 and 10 allowing dentifrice to be discharged onto the bristles. Because of the trough formed on the free end of the bristles this dentifrice will be retained and will not drop off, as is the tendency with flat brushes. This peculiar 15 shape of brush also retains the dentifrice during the operation of brushing the teeth so that the dentifrice instead of only being applied to the few teeth first engaged by the brush will be distributed throughout the set of teeth giving a more thorough cleaning 20 than can be secured with the ordinary brush, unless with this latter brush a number of applications of dentifrice are made thereto. After the dentifrice is applied to the brush, merely turning the same on its pivot 31 will move it to the position shown in Fig. 3 projecting from the opposite end of the handle where it is entirely free for use, and it will be retained therein automatically 25 by the spring 34. When the operator is through using, it may be quickly swung back to its original position shown in Fig. 6 where it will also be retained by the spring 34, the discharge nozzle may be sealed and 30 the whole device inserted in the casing. When it is desired to use the dental floss the desired length may be drawn from the container 44 and cut off by the cutter 52. When the supply of floss is exhausted the 35 cover plate 46 may be moved to one side allowing removal of the old tube 44 and the insertion of a new one having a new supply of floss. When the brush becomes worn or soiled it may be easily and quickly renewed by merely pulling the worn brush 40 from the pivot pin 31, and applying a new brush thereto.

It will be apparent the device is very simple in construction and may be easily kept clean and sanitary. That all the necessary operations are very simple and may be easily and quickly performed. Also that the renewal of any of the supplies as the dentifrice, brush and dental floss may also be easily and quickly performed. Further, that everything is self contained and the completed article makes a simple and neat package which will occupy a small space and may be easily carried.

Having thus set forth the nature of my invention, what I claim is:

1. In combination with a tooth brush having a bristle head, a holding member adapted to carry a dentifrice container having a nozzle provided with a discharge

opening, and pivotal means for connecting the brush to the holding member so positioned that the head may be swung to position the bristles with their free ends arranged along one side of the nozzle adjacent the discharge opening with the opening intermediate the ends of the bristle head so that the brush may receive dentifrice therefrom, or to a position away from the member to allow use of the brush for cleaning purposes.

2. In combination with a tooth brush having a bristle head, a holding member adapted to carry a dentifrice container having a nozzle projecting from one end of the holder, said nozzle being provided with a lateral discharge opening, and means for connecting the brush to said member arranged to allow positioning of the head with the free ends of the bristles along one side of the nozzle and adjacent said discharge opening with the opening intermediate the ends of the bristle head, or spaced from the holder to allow use of the brush for cleaning.

3. In combination a handle, a dentifrice container carried by said handle and provided with a discharge nozzle projecting from one end of the handle, a brush comprising a bristle head and a shank pivoted to said handle, and means for holding the head either in position with the free ends of the bristles along one side of said nozzle to receive dentifrice from said nozzle or projecting from the other end of the handle to allow use for cleaning, said nozzle having a discharge opening intermediate the ends of the bristle head when the head is in dentifrice receiving position.

4. In combination a handle, a dentifrice container carried by said handle and provided with a discharge nozzle projecting from one end of the handle, a brush having a bristle head, means for movably securing the brush to the handle, said means adapted to allow positioning of the head adjacent the discharge nozzle with the free ends of the bristle along one side of said nozzle to receive dentifrice therefrom and also to allow the head to be projected from the other end of the handle in position for using, said nozzle having a discharge opening intermediate the ends of the bristle head when the head is in dentifrice receiving position.

5. In combination a handle, a dentifrice container carried by said handle and provided with a discharge nozzle projecting from one end of the handle, said handle being provided with a recess in one side thereof, a brush having a bristle head and a shank pivoted in said recess and adapted to be swung on said pivot to position the head with the free ends of the bristles along one side of and adjacent said discharge nozzle or to project in the opposite direction.

in position for use, said nozzle having a discharge opening intermediate the ends of the bristle head when the head is in dentifrice receiving position.

5 6. In combination a handle, a dentifrice container carried by said handle and provided with a nozzle projecting from one end of the handle having a lateral discharge opening, a brush having a bristle head with 10 the central bristles shorter than those on the opposite sides thereof, and means connecting the brush to the handle and adapted to position the head and the free ends of the bristles arranged along the side of the 15 nozzle adjacent the nozzle with the opening intermediate the ends of the bristle head and with the shorter bristle in alignment with the discharge opening, and to allow movement thereof away from the nozzle to 20 a position of use.

7. In combination a handle, a dentifrice container carried by said handle and provided with a nozzle projecting longitudinally from one end thereof and provided 25 with a lateral discharge opening, a brush provided with a bristle head having the central longitudinal rows of bristles shorter than those on the opposite sides thereof, and means for securing the brush to the handle 30 with the head at one side of and extending longitudinally of the nozzle and the free ends of the bristles arranged along the side of the nozzle with the shorter bristles in alignment with the discharge opening and 35 with said opening intermediate the ends of the bristle head, said securing means also adapted to allow movement of the head away from the nozzle to a position for use.

8. In combination a handle, a dentifrice 40 container carried by the handle and provided with a discharge nozzle projecting from one end thereof, a brush pivoted to the handle and provided with a bristle head, said pivot being arranged to allow positioning of the head with the free ends of 45 the bristles along one side of and adjacent the nozzle to receive dentifrice therefrom or projecting from the other end of the handle, said nozzle having a discharge opening intermediate the ends of the bristle head when 50 the head is in dentifrice receiving position, and a spring bearing on said brush and arranged to hold it in either position.

9. In combination a handle, a brush having 55 a shank, a pivot pin carried by the handle, said shank being resilient and slit at its end and provided with a transverse opening communicating with said slit, said slit and opening arranged to allow lateral insertion of the pin into said opening through the slit.

10. In combination a handle, a trans-

versely extending pivot pin carried by said handle, a brush provided with a bristle head and a shank, said shank being resilient and slit at its end, said slit being adapted to receive said pin to secure the shank thereto. 65

11. In combination a handle, a brush provided with a bristle head and a shank, means for pivotally securing the shank to the handle and so constructed and arranged that the shank may be secured to or removed from the handle by movement thereof longitudinally of the shank. 70

12. In combination a handle, adapted to 75 carry a dentifrice container, a tooth brush secured to said handle and adapted to receive dentifrice from said container, said handle being provided with a pocket between the container and brush adapted to 80 hold a supply of dental floss and means for closing the opening to said pocket.

13. In a device of the character described a handle adapted to carry a dentifrice container and a brush, said handle being provided with a pocket leading from one end thereof to carry a supply of dental floss, a cover plate movably secured to the end of the handle to cover the entrance to said pocket, and means for positioning the plate 90 in closed position. 85

14. In a device of the character described a handle adapted to carry a dentifrice container and a brush, said handle being provided with a pocket leading from one end 95 thereof to carry a supply of dental floss, a cover plate movably secured to the end of the handle to cover the entrance to said pocket, said cover plate being arranged to clamp the free end of the floss against the 100 handle and provided with a recess to allow passage of the floss.

15. In a device of the character described a handle adapted to carry a dentifrice container and a brush, said handle being provided with a pocket leading from one end thereof to carry a supply of dental floss, a cover plate movably secured to the end of the handle to cover the entrance to said pocket, said cover plate being provided with 105 means to allow passage of the floss and a cutter to sever the same. 110

16. In a device of the class described a tubular casing open at one end and provided with notches on the opposite sides of said open end, a brush and handle adapted for insertion in said casing, said handle being provided with recesses on its opposite sides in alignment with the recesses in the casing, the inner ends of the recesses in the casing 120 being bent inwardly to yieldingly engage the walls of the recesses in the handle.

In testimony whereof I affix my signature.
ROBERT H. LIEBERTHAL.
